WINCENTY KRYGOWSKI, OF CHICOPEE FALLS, MASSACHUSETTS.

COMBINED MOTOR AND AIR-COMPRESSOR.

No. 917,081.

Specification of Letters Patent.

Patented April 6, 1909.

Application filed November 11, 1908. Serial No. 462,034.

To all whom it may concern:

Be it known that I, WINCENTY KRYGOWSKI, an Austro-Hungarian subject, and resident of Chicopee Falls, in the county of 5 Hampden and State of Massachusetts, have invented certain new and useful Improvements in a Combined Motor and Air-Compressor, of which the following is a full, clear, and exact description.

10 This invention relates to a combined explosive gas motor and an air compressor and is in part characterized by the inclusion of the combined motor and compressor within the reservoir in which compressed air is delivered from the compressor,—the effect of entrance of the compressed air to the reservoir tending, measurably, to cool the motor while the heat of the motor is directly efficient for expanding and increasing the compression of the air in the reservoir.

15 Another object is to utilize the heat of the muffler within the compressed air reservoir for additional air expanding effect.

Another object is to utilize the compressed 20 air produced by the apparatus effectively in conjunction with the carbureter for the motor.

Another object is to separate the cylindrical chamber in which the motor piston 25 works from the chamber with which the carbureter is connected and in which the explosion initially occurs, with valve arrangements so that at the time of exhausting dead gas from the piston chamber, concurrently 30 with the intake of a fresh mixture, there will be no commingling of one with the other.

Another object is to provide means whereby on the establishment of an excessive pressure in the reservoir the apparatus will automatically cease its operation.

40 The invention consists in the combinations or arrangements of the devices and parts all substantially as hereinafter described in conjunction with the accompanying drawings 45 and set forth in the claims.

In the drawings:—Figure 1 is a longitudinal sectional view taken on line 1—1, Fig. 2, and shows the interior of the air-reservoir and the contained air-compressing mechanism, certain parts of the latter being shown in full lines; Fig. 2 is a transverse section taken on line 2—2, Fig. 1; Fig. 3 is a detail view of a portion of the controlling devices and is partly in section, the line of section being indicated by line 3—3, Fig. 1. Fig. 4 is a

side elevation on a larger scale, for more clearly indicating certain valve arrangements hereinafter particularly described.

In the drawings,—A is a horizontally supported cylindrical reservoir of a suitable construction to hold air under pressure. The bottom portion of the wall of the reservoir A has formed therein an irregular shaped, longitudinally extending opening, to the boundary edges 10 of which are riveted the 60 flanged uniting supports 12, of the air-compressor B, the somewhat irregular contour of the air-compressor at its line of junction with edges 10 of the reservoir opening conform exactly to the said edges 10 to the important end that a rigid support of the air-compressor B to and within the air-reservoir A is provided in a manner which does not impair the air-tight requirements of the air-reservoir.

75 The air-compressor B, which is automatic in its action, consists of an air-compressing cylinder C, and an axially opposed gas-explosion engine cylinder D; the body portion of these cylinders are preferably united in one 80 integral construction as shown in Fig. 1. The piston 15 of the air-cylinder C is rigidly connected to the piston 16 of the gas-engine D by the piston rod 17, whereby an explosion actuated stroke of the piston 16 transmits 85 through piston rod 17 an air compression stroke to the piston 15, and the return stroke of the piston 16, and the air-suction stroke of piston 15 is provided for by the retractile force of the heavy spiral spring 18 (see Figs. 90 1 and 3), one end of which is attached to the air-piston 15 and the opposite end to a stud 19 in the slide chamber 20 of the cylinder D. The air-compressing cylinder C has a head 21 through which the air inlet 22, and air 95 outlet 23, are provided. The air-inlet 22 is equipped with the inlet valve 24, which is opened into the air-cylinder by the suction stroke of the air-piston 15 and against the action of the light valve-closing spring 25. The 100 air inlet is connected with the outside or atmospheric air by the inlet-pipe 26 which, as shown in Fig. 1, may be an integral part of the cylinder head 21, and which projects therefrom through the reservoir head a'. The outlet 23 for the compressed air is 105 equipped with the outwardly opening hinged valve 27, which is opened for the expulsion of air from the air cylinder C by the action of the compression stroke of the air-piston 15, 110

and against the valve closing spring 28. The outlet for the compressed air through the cylinder head 21 is thence downwardly through the elbow-provided pipe 29, which also may be an integral part of the said cylinder head; from pipe 29, the compressed air from cylinder C is conducted through the horizontal pipe 29^a underneath the air-compressor B, and thence upwardly by the vertical pipe 29^b 10 to a point somewhat above the top of the air-compressor B from which the short horizontal pipe 29^c which passes through the reservoir head a to a point therein just above the explosion chamber 31 of the gas engine D, where a downwardly turned elbow directs the discharge of the compressed air conducted through the pipe connections 29, 29^a, 29^b, 15 and 29^c, against the explosion chamber casting and provides an efficient means for cooling the same.

The gas-explosion cylinder D has a chambered head 30 comprising an explosion chamber 31 and an exhaust chamber 32; the inside wall 33 of the explosion chamber has provided therein the valve port 34, leading to the interior of the cylinder D, this port 34 being normally closed by the spring actuated valve 35. The inside wall 36 of the exhaust chamber 32 has provided therein the exhaust port 37 leading from the cylinder D which is normally closed by the valve 38. This valve 38, which is automatically closed by its spring 39, has a long sliding valve stem 40, the outer or free end portion of which is provided with a collar-like abutment 41.

A downwardly extending arm 42 adjustably mounted on the piston rod 17 has a hole 43, through which the valve-stem 40 freely slides, whereby, as shown in Fig. 1, the latter portion of the working stroke of piston 16 40 carries the arm 42 into engagement with the abutment 41 of the stem of valve 38 and opens the same.

The underneath side of valve stem 40 is provided with ratchet teeth 44, which are engaged by the hinged and upwardly pressed spring pawl 45, to the end that any degree of opening of the exhaust valve 38 produced by engagement of the valve-stem 40 with the 50 piston rod arm 42, is maintained thereby during the spring actuated return stroke of piston 16. At the extreme latter portion of this return stroke, however, the angularly bent end 47 of arm 42 engages the pendent lug 48 formed on pawl 45 and swings the latter from engagement with the ratchet 44, thus permitting the instantaneous closing of the exhaust valve 38.

The dead gas or products of combustion 60 exhausted from the cylinder D as above described, is not discharged into the outer air, but is conducted by the pipe 50 from the under side of the exhaust chamber 32, rearwardly and thence upwardly and into the 65 reservoir A to the horizontally supported

muffler 51, where the heat is retained for a brief time before the gas is finally allowed to escape to the outer air through the pipe 52.

Simultaneously with the closing of the exhaust valve 38, the plunger cut-off valve 38^a 70 which is forced against its spring 38^b from its closing position over the entrance to exhaust pipe 50 (as shown in Fig. 1) by the pressure of the exhaust gas, instantly resumes its closing position over the entrance to pipe 50, 75 on the closing of the exhaust valve 38.

The novel form of carbureter which I employ together with the automatic controlling devices employed in conjunction therewith will now be described.

At a point below the reservoir A and adjacent the gas-engine D is supported the chambered carbureter casing E into which gasolene is conducted through the supply pipe 60, the vertical conduit 61 in the casing 85 E for the intake of gasolene discharges into a horizontal pump bore 62, one end of which is normally closed by a spring pressed valve 63, and the opposite end is suitably bored to receive the pump plunger or piston 64. At a point directly below the pump plunger 64 is the air inlet from which a branch pipe 65^a extends to a T connection with the compressed air pipe 29^a.

Combined with, and supported on, the 95 above mentioned T-connection is the plug-valve 66, the valve plug of which has formed thereon the lever arm 67. A pivoted three-arm member d is mounted on the upper or horizontal portion of the T coupling, one of 100 its arms 68 being connected by a link 69 with the valve plug arm 67, and an oppositely extending lever arm 70 connects with the pump-plunger 64, through the connecting rod 71. The third arm 72 of the member d, which 105 extends nearly vertically upward from the T coupling is in the path of movement of the end portion 47 of the piston arm 42, and is engaged thereby previous to the termination of the spring actuated return stroke of the 110 pistons 15 and 16, with the result that the entire three-arm member d is rotated a one-quarter turn, thereby opening the valve 66, which allows a portion of the compressed air in the pipe 29^a to be diverted through pipe 115 65^a into the carbureter E; and at the same time an impulse is given the pump-plunger 64 which acts to force the small amount of gasolene which has entered the pump bore 62, from the supply pipe 60 out, against the 120 spring pressed valve 63, when it is instantly mixed with the compressed air from the pipe 65^a, and the mixture thus produced is forced upward from the carbureter E through the connecting bent pipe 74, into the explosion 125 chamber 31 of the gas-engine, the spring seated closure valve 75 automatically opening to admit the mixture. Simultaneously with the completion of the above described spring-actuated return stroke of the pistons

15 and 16, and the attendant charging of the explosion chamber 31 with the explosive mixture of gasoline and compressed air as described, the end 47 of piston arm 42 engages the pendent portion 48 of pawl 45, and causes the said pawl to release the exhaust-valve stem 40, thereby instantly closing the exhaust port 37; and also at the same instant the insulated contact point 76 of an 10 electric circuit, which is carried on the valve stem 40, engages a stationary contact point 77, which is in circuit with a spark plug 78 in the explosion chamber 31 with the result that the contained explosive mixture is ignited and the forward or working stroke of the 15 pistons 15 and 16 is effected. As the compressed air is forced into the reservoir A through the elbow discharge end of pipe 29^a, it not only serves to cool the explosion end of 20 the gas engine D, but it is itself expanded by the heat of the explosions, which it takes up, and is also still further expanded by taking up the not inconsiderable amount of heat from the exhaust gas which is for a time held in 25 the muffler 51 within the reservoir A.

The compressed air for purposes desired is taken from the reservoir A through the service pipe F, and in the event of a cessation of compressed air being drawn from the reservoir, a safeguard against the accumulation 30 of a dangerous pressure, and also against the wasteful running of the compressor B is provided by the upwardly spring pressed, yielding plunger 80, which has an operative engagement with the hinged stop bar or 35 detent 81, the free end 82 of which is moved downwardly and into the path of movement of the stop 83, on piston arm 42, when too great a pressure is exerted on the upward face of 40 plunger 80, the result of the impact of the free end 82 of the detent 81 being to hold the pistons 15 and 16 in their forward or working position against the tension of the returning spring 18.

45 A small air-compressor 90, which may be operated by hand, is provided for the initial storing of the tank with compressed air which is necessary, as a certain amount of air pressure within the pipes 29^a and 65^a is 50 required to provide the proper explosive in the carbureter E where it unites with the injected gasoline supply as described.

By provision of the partition 33 whereby the chamber 31 is produced separate from the chamber of the cylinder D in which the piston 16 works, it becomes practicable to maintain the exhaust valve 38 open from its port for a short, though comparatively considerable, period to permit of an entire 55 expulsion of dead gas from the piston cylinder even while there is a fresh intake of explosive gas from the carbureter into the chamber 31 with no liability of the dead gas becoming mixed with the fresh intake.

I claim:—

65

1. In an apparatus of the character described, a reservoir for compressed air, and a combined motor and air compressor internally of the reservoir, the compressed air delivery conduit terminating within the reservoir. 70

2. In an apparatus of the character described, a reservoir for compressed air, and a combined explosive gas motor and air compressor internally of the reservoir, the compressed air delivery conduit terminating 75 within the reservoir, and directed against the motor.

3. In an apparatus of the character described, a reservoir for compressed air, a combined explosive gas motor and air compressor internally of the reservoir, the compressed air delivery conduit terminating 80 within the reservoir, a muffler within the reservoir, a conduit leading from the dead 85 gas outlet of the motor to the muffler, and a conduit leading from the muffler to the interior of the reservoir.

4. In an apparatus of the character described, a reservoir for compressed air, a combined explosive gas motor and air compressor comprising pistons and a single rod uniting both pistons, the compressed air delivery conduit of the compressor terminating 90 within the reservoir, the motor having in addition to a cylindrical chamber for the motor piston a separate chamber for exhaust gas, a port leading from the cylindrical piston chamber to said exhaust chamber, and a valve for said port having an elongated 100 valve stem, means for opening said valve on the working stroke of the combined pistons, a detent pawl for engaging the valve stem and holding the valve in its opened position, and means for releasing said detent on the 105 reversed stroke of the pistons.

5. In an apparatus of the character described, a reservoir for compressed air, a combined explosive gas motor and air compressor comprising pistons, and a single rod 110 uniting both pistons, provided with a transverse projection, the compressed air and delivery conduit terminating within the reservoir, the motor having in addition to a cylindrical chamber for the motor piston a separate chamber for exhaust gas, a port leading 115 from the cylindrical piston chamber to said exhaust chamber, and a valve for said port having an elongated valve stem provided with a shoulder to be engaged by said piston rod projection on the working stroke of the pistons for operating said valve, a detent pawl for engaging said valve stem and holding the valve in its opened position, said detent pawl being in the path of reversed movement of said piston rod projection. 120 125

6. In an apparatus of the character described, a reservoir for compressed air, a

combined explosive gas motor and air compressor located within the reservoir, comprising aligned piston cylinders and pistons therein, and a rod connecting both pistons, 5 having a transversely extending projection, a gas outlet port leading from the piston cylinder of the motor, having an elongated stem parallel with said piston uniting rod, intermediately provided with a series of 10 ratchet teeth, and having at its extremity a shoulder, a spring exerting a valve closing force on said stem, a spring pressed detent pawl adapted to engage said ratchet teeth, and provided with an arm, and said piston 15 rod projection having a path of movement to alternately engage the valve rod shoulder, and the detent pawl arm, for the purposes set forth.

7. In an apparatus of the character described, 20 a reservoir for compressed air, a combined explosive gas motor and air compressor comprising pistons and a single rod uniting both pistons, the compressed air delivery conduit of the compressor terminating within the reservoir, the motor having in addition to a cylindrical chamber for the motor piston a separate chamber for exhaust gas, a port leading from the cylindrical piston chamber to said exhaust chamber, and a 25 valve for said port having an elongated valve stem, means for opening said valve on the working stroke of the combined pistons, a detent pawl for engaging the valve stem and holding the valve in its opened position, and means for releasing said detent on the reversed stroke of the pistons, and a muffler within the reservoir, a conduit leading from the said exhaust chamber to the muffler and a conduit leading from the muffler to the exterior 30 of the reservoir.

8. In an apparatus of the character described, 40 a reservoir for compressed air, a combined explosive gas motor and air compressor comprising pistons and a single rod uniting both pistons, the compressed air delivery conduit of the compressor terminating within the reservoir, the motor having in addition to a cylindrical chamber for the motor piston a separate chamber for exhaust gas, 45 a port leading from the cylindrical piston chamber to said exhaust chamber, and a valve for said port having an elongated valve stem, means for opening said valve on the working stroke of the combined pistons, a 50 detent pawl for engaging the valve stem and holding the valve in its opened position, and means for releasing said detent on the reversed stroke of the pistons, a muffler within the reservoir, a conduit leading from the said 55 exhaust chamber to the muffler, a conduit leading from the muffler to the exterior of the reservoir, and a spring pressed valve for normally closing communication from the exhaust chamber through the conduit leading thence to the muffler.

9. In an apparatus of the character described, a compressed air reservoir, a combined motor and air compressor located therewithin comprising aligned motor and compressor pistons and a rod for uniting 70 them, having an abutment, a plunger or diaphragm subject to the pressure of air in the reservoir, and a device actuated by said diaphragm, under excessive air pressure in the reservoir, for engaging said abutment and 75 preventing movement of the rod united pistons.

10. In an apparatus of the character described, a compressed air reservoir and an air compressor therewithin having combined 80 therewith a motor the working piston of which has a rod connecting it with the working piston of the compressor and said rod having an abutment, a conduit leading from the compressor cylinder to within the reservoir, a plunger or diaphragm subject to the 85 pressure of air in the reservoir and a pivoted lever actuated by the diaphragm under an excessive air pressure and adapted to be swung to a position for engaging and intercepting the movement of the said abutment 90 of the piston connecting rod.

11. In an apparatus of the character described, a combined explosive motor and air compressor having axially aligned piston cylinders, pistons working therein and a rod connecting both pistons, a spring operating on the combined pistons for retracting them after each working stroke, a carburetor for the motor comprising a chamber pipe connected with the valved inlet port of the motor and having a bore, a liquid fuel conduit leading to said bore, a spring valve closing the junction between said bore and said chamber, a plunger working in the bore, and 100 means actuated by the retractile movement of the combined pistons for imparting a 105 thrust to said plunger.

12. In an apparatus of the character described, a combined explosive gas motor and 110 air compressor comprising aligned cylinders and working pistons therein connected by a common piston rod and a compressed air delivering conduit connected with the air compressing cylinder, a carburetor for the explosive gas motor comprising a mixing chamber, liquid fuel supplying means therefor, a pipe leading from the compressed air delivery conduit to said mixing chamber and having a valve, a valve operating lever connected with 115 said valve and a projection on the piston uniting rod adapted to periodically engage said valve operating lever for admitting compressed air to the mixing chamber.
